UNITED STATES PATENT OFFICE.

EMORY CROUSE, OF WICHITA, KANSAS.

INTERNAL-COMBUSTION ENGINE.

1,344,263.

Specification of Letters Patent. Patented June 22, 1920.

Application filed November 20, 1919. Serial No. 339,307.

To all whom it may concern:

Be it known that I, EMORY CROUSE, a citizen of the United States, residing at Wichita, in the county of Sedgwick and 5 State of Kansas, have invented certain new and useful Improvements in Internal-Combustion Engines, of which the following is a specification.

This invention relates to internal combustion engines, particularly to those of the two-cycle type, and has for its object the provision of an engine in which are provided compression cylinders auxiliary to the working or explosive cylinders and for 15 the purpose of initially compressing a charge of vaporized fuel prior to its passage into the working cylinders, the advantage being an increase in power.

An important object is the provision of 20 an engine of this character which is equally well adapted for the use of either light or heavy oils as fuel owing to the provision of means for preheating the charge within the compression cylinders so as to increase its 25 explosive qualities before its introduction within the working cylinders, a distinctive feature being the provision of annular chambers surrounding the compression cylinders into which chambers passes, optionally, the 30 exhaust from the working cylinders.

An additional object is the provision of 35 an engine of this character which is valveless and which therefore eliminates the use of elaborate valve operating mechanism, and consequently renders the engine inexpensive and simple in construction, economical and efficient in use, durable in service, and a general improvement in the art.

With the above and other objects and advantages in view, the invention consists in 40 the details of construction and arrangement of parts to be hereinafter more fully described and claimed, and illustrated in the accompanying drawings, in which—

45 Figure 1 is a side elevation of the intake side of the engine,

Fig. 2 is a side elevation of the exhaust side,

Fig. 3 is a longitudinal sectional view, and

50 Fig. 4 is a horizontal sectional view.

Referring more particularly to the drawings, the numeral 10 designates the crank case of the engine upon which is secured the cylinder casting 11 having formed therein 55 cylinders 12, 13, 14 and 15, the former being compression and the latter explosive cyl-

inders. The usual crank shaft 16 is provided which is of course connected by connecting rods 17 with the pistons 18, 19, 20, and 21 in the respective cylinders.

The explosive cylinders 14 and 15 are provided with spark plugs 22 as shown. These cylinders are surrounded by a water jacket 23 having an inlet pipe 24 and an outlet pipe 25. It will be noted that this water 60 jacket does not extend around the cylinders 12 and 13, which are, instead, surrounded by chambers 26 and 27, respectively, which are open to the atmosphere through ports 28. The cylinders 12 and 13 are provided at 70 their upper portions with ports 29 leading into by-passes 30 and 31 which communicate with ports 32 in the intermediate portions of the cylinders 14 and 15, respectively.

The intake comprises a manifold 33 leading from any ordinary or preferred carburetor, shown conventionally at 34, and communicating with the intermediate portions of the cylinders 12 and 13 through ports 35. This carburetor and manifold are for the 75 use of light and highly volatile fuels such as gasoline. To permit the use of heavy oils or fuel, I provide a manifold 36 which leads into the cylinders 12 and 13 through small jets 37 and which is connected with 80 any suitable constant level oil feed, indicated conventionally at 38. Either manifold may be used as will be hereinafter explained.

Formed in the cylinders 12 and 13, at points preferably diametrically opposite the 85 ports 35, are ports 39 which communicate with the chambers 26 and 27 and formed in the cylinders 14 and 15 are exhaust ports 40, and all of these ports communicate with an exhaust manifold 41 which is of Y shape 90 and which has its descending or outlet branch 42 provided with a butterfly valve 43 and any suitable means for operating the same.

The operation of the engine is as follows: 100 When it is desired to operate with gasoline or any other suitable highly volatile fuel, the flow of heavy oil to or through the manifold 36 is cut off by any preferred means and the fuel is delivered to the cylinders 105 through the manifold 33 and ports 35. When heavy oils are used the flow to or through the manifold 33 is cut off and fuel is delivered to the cylinders through the manifold 36 and the spray jets 37. Regardless of which form of fuel is used, the operation of the engine is the same. When the 110

pistons 18 and 19 are at the tops of their strokes and move downwardly, a partial vacuum is formed to the rear of them until the pistons pass the ports 35, or jets 37, 5 whereupon a charge of fuel will be sucked very violently into the cylinders 12 and 13, and the violence of this intake will assist materially in breaking up the fuel into a more highly explosive vapor. As the pistons 18 and 19 move upwardly the pistons 20 and 21 move downwardly and the mixture within the cylinders 12 and 13 will be compressed in advance of the pistons 18 and 19 until the pistons 20 and 21 pass the 10 ports 32 whereupon the compressed charges will enter the cylinders 14 and 15 through the by-passes 30 and 31. As the pistons 20 and 21 subsequently move upwardly they will compress the charges still more until 15 they reach the upper ends of their strokes whereupon explosion occurs and the pistons 20 and 21 are forced downwardly on their working strokes. When the pistons 20 and 21 reach their downward limits they will 20 uncover the exhaust ports 40 and the burnt gases will be discharged into the exhaust manifold 41. It will be observed that the two sets of compression and working pistons operate in alternation.

25 When using heavy oils as fuel, it is highly desirable and in fact necessary that the fuel be heated before entering the cylinders 14 and 15. In order to accomplish this, it is merely necessary to move the valve 43 to partly or entirely close the outlet of the 30 exhaust manifold. The exhaust gases from the cylinders 14 and 15 will then pass through the manifold 41 and through the ports 39 into the chambers 26 and 27 surrounding the compression cylinders 12 and 13 and these cylinders will consequently be greatly heated, thus efficiently vaporizing the fuel issuing from the jets 37 so as to provide a highly explosive charge. The 35 exhaust then passes from the chambers 26 and 27 into the atmosphere through the ports 28. By only partly closing the valve 43 the amount of exhaust passing into the heating chambers may be readily regulated so as to 40 avoid overheating of the engine.

45 From the foregoing description and a study of the drawings, it will be apparent that I have thus provided a simple and inexpensive engine which is free from valves and all of the mechanism required for their 50 operation, which will be powerful owing to

the double compression, which is capable of using either light or heavy oils as fuel, which is provided with means for preheating the fuel when necessary or desired, and 55 which will efficiently perform all the functions for which it is intended.

60 While I have shown and described the preferred embodiment of the invention, it will of course be readily understood that I 65 reserve the right to make such changes in the form, construction, and arrangement of parts as will not depart from the spirit of the invention or the scope of the subjoined claims.

70 Having thus described my invention, I claim:

1. In an internal combustion engine, a pair of working cylinders, a pair of compression cylinders communicating therewith through by-passes, the compression cylinders having hollow walls defining annular chambers, means for supplying fuel to the compression cylinders, said working cylinders having exhaust ports communicating with an exhaust manifold, said annular chambers having ports communicating with the exhaust manifold and other ports leading to the atmosphere, said exhaust manifold having an outlet to the atmosphere, 80 and a butterfly valve within said outlet whereby all or part of the exhaust gases may be deflected into said chambers.

85 2. In an internal combustion engine, a pair of working cylinders, a pair of compression cylinders communicating therewith through by-passes, the compression cylinders having hollow walls defining annular chambers, a heavy fuel manifold and a light fuel manifold leading to inlet ports in said 90 compression cylinders and selectively usable, said working cylinders having exhaust ports communicating with an exhaust manifold, and said annular chambers having ports communicating with the exhaust manifold 100 and other ports leading to the atmosphere, and means within the exhaust manifold whereby the exhaust may be permitted to pass therefrom when the light fuel is used or to deflect the exhaust into said chambers 105 when the heavy fuel is used whereby to assist in vaporization thereof in the compression cylinders.

110 In testimony whereof I hereto affix my signature.

EMORY CROUSE.
